(57) **CLAIM**

The ornamental design for a strap for a shoe, as shown and described.

DESCRIPTION

FIG. 1 is a perspective view of a strap for a shoe, showing my new design;

FIG. 2 is a side view thereof;

FIG. 3 is a front view thereof;

FIG. 4 is an opposite side view thereof;

FIG. 5 is a rear view thereof;

FIG. 6 is a top view thereof;

FIG. 7 is a bottom view thereof;

FIG. 8 is a perspective view of a strap for a shoe, according to a second embodiment of the present invention;

FIG. 9 is a side view thereof;

FIG. 10 is a front view thereof;

FIG. 11 is an opposite side view thereof;

FIG. 12 is a rear view thereof;

FIG. 13 is a top view thereof; and,

FIG. 14 is a bottom view thereof.

The broken lines shown in the Figures are for environmental purposes only and form no part of the claimed design.

1 Claim, 8 Drawing Sheets
